DESIGN FOR A POURER CAP

**Philip A. Derham and Jesse H. Newport, Jr.,
Rosemont, Pa., assignors to Victor Metal Products Corporation, Brooklyn, N. Y., a corporation of New York**

Application October 18, 1941, Serial No. 103,812

Term of patent 7 years

To all whom it may concern:

Be it known that we, Philip A. Derham and Jesse H. Newport, Jr., citizens of the United States and residents of Rosemont, in the county of Montgomery and State of Pennsylvania, have invented a new, original, and ornamental Design for a Pourer Cap, of which the following is a specification, reference being had to the accompanying drawing, forming part thereof.

Fig. 1 is a top plan view of a pourer cap showing our new design.

Fig. 2 is a front elevational view of the same.
Fig. 3 is a horizontal sectional view taken on the line 3—3 of Fig. 2.

We claim:

The ornamental design for a pourer cap, substantially as shown.

PHILIP A. DERHAM.
